BUILDER'S HARDWARE

Elvin H. Johnson, Winnetka, Ill.

Application March 14, 1932, Serial No. 598,771

6 Claims. (Cl. 292—278)

My invention relates to builders' hardware and includes among its objects and advantages the provision of an improved door holder.

In the accompanying drawings:

Figure 1 is a side elevation of a portion of a door showing my invention applied thereto;

Figure 2 is a sectional view taken along the line 2—2 of Figure 1;

Figure 3 is an enlarged sectional view taken along the line 3—3 of Figure 1;

Figure 4 is a sectional view taken along the line 4—4 of Figure 1;

Figure 5 is a side elevation of a portion of the door holder;

Figure 6 is a plan view of the structure shown in Figure 5;

Figure 7 is a sectional view taken along the line 7—7 of Figure 6;

Figure 8 is a view illustrating the releasing mechanism;

Figure 9 is a sectional view taken along the line 9—9 of Figure 7;

Figure 10 is a perspective of a cam member;

Figure 11 is a perspective view of a sleeve associated with the cam member;

Figure 12 is a perspective view of a washer associated with the sleeve;

Figure 13 is an end view of a portion of my device; and

Figure 14 is a diagrammatic view illustrating the door holder applied to a door of the double acting type.

The embodiment selected to illustrate the invention is for use with either single or double-acting doors and comprises an arm 10 pivotally connected at 12 (see Figure 2) with a door bracket 14. A recess 16 is cut in the upper end of the door 18 for receiving the bracket. Screws 20 secure the bracket to the door. The opposite end of the arm is pivotally connected at 22 with a sliding bar 24 associated with a guide member 26. The guide member 26 is positioned within a recess 28 in the casing 30 with which the door 10 is associated through the medium of spring hinges 32 which tend to close the door. Screws 33 secure the guide member to the casing. The bar 24 is arranged to slide to and fro along the guide member 26 to permit the door to be moved upon its hinges 32 in the ordinary manner.

In Figure 4 I have detailed the pivotal connection between the arm 10 and the door bracket 14. The pivotal connection comprises a pintle 34 having a cylindrical portion 36 passing through an opening 38 in the arm 10 and a threaded portion 40 threaded through the door bracket

14. This construction makes the nut 42 a mere lock nut to keep the pintle from shifting and tightening or loosening the connection between the arm 10 and the bracket 14. Means for holding the nut 42 against relative movement on the threaded portion 40 comprises a lock washer 44 positioned upon the threaded portion 40 between the nut 42 and the bracket 14. The cylindrical portion 36 is slightly longer than the opening 38, so that its end contacts with the bracket 14. Thus it will be seen that while the pintle is firmly secured against relative movement with the bracket 14, the cylindrical portion 36 is permitted rotative movement within the opening 38. A thin washer 46 is placed between the arm 10 and the bracket 14 upon the cylindrical portion 36. This washer separates the arm 10 from the bracket 14 a desirable distance so that complete freedom of movement between these two parts is permitted. The head 48 of the pintle is positioned within a recess 50 in the arm 10 substantially flush with the upper face of the arm.

The pivotal connection 22 between the arm 10 and the bar 24 comprises a pintle 52 (see Figure 3) having a cylindrical portion 54 passing through an opening 56 in the arm 10. The threaded portion 58 of the pintle is threaded into the sliding bar 24. When the pintle is turned down to the position shown in Figure 3, the end of the cylindrical portion 54 will bear against the sliding member 24 so that the pintle is held against turning relatively to the sliding bar. Thus it will be seen that the arm 10 is permitted rotative movement upon the cylindrical portion 54. The head 60 of the pintle 52 is positioned within a recess 62 in the arm 10.

It will be noted in referring to Figure 3, that the sliding bar 24 is substantially T-shaped in cross section, and that the guide member is slotted and grooved to conform to the shape of the sliding bar. Both parts are made from material of the same thickness. One end of the sliding bar is cut away as at 64 (see Figure 6) to provide a head 66. This head is provided with a cam surface 68 and a recess 70 for receiving a roller 72 (see Figures 5, 7, and 8) when the door has been moved to its open position as illustrated in Figure 2. The roller 70 is loosely mounted upon a pin 74 carried by one end of a lever 76. The lever is positioned between a pair of lugs 78 formed integrally with the carriage and fulcrums upon a pin 80 carried by the lugs. The normal position of the lever when the head 66 is disengaged from the roller end, is indicated in Figure 5. Shoulders 79 upon the lever 76 en-

- gage the lugs 78 for limiting the downward movement of the roller end of the lever so that the roller cannot move below the lower end of the cam surface 68. The lever is yieldingly held in this position by means of a spring 82 mounted upon a sleeve 84 pivotally connected with the other end of the lever by a pin 86. One end of the spring bears against the lever while the opposite end rests upon a washer 88 (see Figures 7 and 12).
10 In Figure 6 I have shown the slot 90 in the end of the lever for receiving the flattened end 92 of the sleeve. When the door 10 has been moved substantially to its full open position, the cam surface 68 engages the roller 72 and lifts the roller end of the lever 76 which compresses the spring 82. As soon as the head 66 has been moved sufficiently far to properly align the recess 70 with the roller 72, the latter will snap into the recess by reason of the spring 82. The roller 72 is resiliently urged in the direction of the head 66 with a force sufficient to hold the door against a closing force materially greater than that of the closing spring for the door but materially less than the hinges will stand without injury, so 25 that the application of a reasonably small additional force will enable the user to close the door merely by pushing on it.
I find that good results can be obtained by positioning the door holder with respect to the hinges 32 in such a manner that the head 66 of the sliding member will be connected with the lever 76 when the door has been swung 90° from its closed position. It is desirable to provide cushioning means for damping the shock occurring when the door is moved abruptly to the open position shown in Figure 2. I have illustrated a block 94 which is positioned in a spring chamber 96 transversely of the head 66. The head is shaped to pass between the lugs 78 against which 30 the block 94 is yieldingly held by means of a pair of springs 98. The block is bored at 100 for receiving pins 102 upon which the springs 98 are mounted. One end of each spring bears against the end of the spring chamber, as at 104. The 45 springs are placed in position with the necessary amount of initial tension. The pins 102 are threaded upon their inner ends 106 and threaded into openings 108 in the guide member. This feature is clearly brought out in Figure 7. A screw driver may be inserted in slots 110 in the exposed ends of the pins for assembling or removing the mechanism associated with the pins.
The end of the head 66 bears against the block 94 when the roller 72 is finally positioned within 50 the recess 70. When the head 66 strikes the block 94, any remaining force in excess of that which is necessary to swing the door to its open position is absorbed in the compression of the springs 98. Shoulders 112 limit the amount the 55 springs may be compressed by striking against the edges 114 of the lugs 78. Such striking does not generally occur during the normal opening and closing of the door. Referring now to Figure 7, I have shown the manner in which the lever 76 is moved during the cushioning action. It will be noted that one side of the recess 70 inclines gently as at 115, so that the roller 72 may move easily up the incline when the door is moved beyond its normal open position. The cushioning 60 function of the springs 98 is effective only during such movement of the roller up the incline. In Figure 7, the full line illustration of the lever and the head 66 shows the manner in which the cushioning function is brought about, and the dotted line showing illustrates the roller posi-

tioned in the recess for holding the door in the open position shown in Figure 1. As soon as the excess force has been absorbed, the springs 98 move the head 66 back to the dotted line position and the roller comes to rest at the bottom of the recess 70.

I have provided means for rendering the door holder inoperative for holding the door open. In Figure 7, I have shown the washer 88 as being positioned upon a slidable cam block 116. In 10 Figure 8 the cam block is shown as being shifted sufficiently forward to render the spring 82 inoperative for holding the roller 72 in the recess 70. In referring to Figure 9, it will be noted that the sleeve 84 is slidably mounted upon a pin 118 15 secured to the bottom of the spring chamber 96. The lower end of the sleeve is flattened at 120 and slidably positioned within a slot 122 in the cam block. The lower end of the sleeve passes through the washer 88 and is provided with 20 flanges 124 for preventing the washer from dropping off the sleeve when it is not supported by the cam block. Referring now to Figure 13, it will be noted that the end of the guide member is slotted as at 126, and is provided with ribs 25 128 which ride within grooves 130 in a grip member 132 which is welded to the cam block. The cam block is of material having high wear resisting properties. The grip portion 132 is of the same material as the carriage 10 to eliminate 30 color contrast. The grip member 132 terminates substantially flush with the lower face of the guide member, as illustrated in Figure 8. Ordinarily the flange 124 will rest upon the thin extensions 134 upon the cam block when it is 35 shifted to the position shown in Figure 8. The cam block may be easily shifted for lifting the washer to a position where it will rest upon the upper face of the cam block, as shown in Figure 7. When the cam block is positioned as in Figure 40 8, the door may be opened and closed without being influenced by the lever 76.

The door holder is substantially concealed from view and is so constructed that no parts project beyond the casing or the door when the 45 door is closed. I have recessed the guide member 26 to accommodate the arm 10, so that no part of the arm will project beyond the contour of the guide member when the door is in its closed position. This construction provides a 50 compact arrangement of the parts.

In Figure 14, I have illustrated my door holder in connection with a door 136 of the double-acting type. The guide member 26 is shown as being fastened to the door rather than the door casing. In any installation, the guide member may be associated with the door or the door casing. I have shown the door 136 associated with a wall structure 138, and the door provided with the usual hinge means 140 of the type permitting the door to swing to a full open position in either direction, as illustrated.

Without further elaboration the foregoing will so fully explain my invention that others may, by applying current knowledge, readily adapt the same for use under various conditions of service.

I claim:

1. The combination with a casing element and a door element hingedly associated therewith, of a guide structure embedded in one of said elements, a slide member associated with said guide structure and having a cam surface and a holding surface, a link having one end pivotally connected with said slide member and the oppo- 70 75 75

- site end pivotally connected with the other of said elements, a roller normally mounted in the path of said cam surface, means for yieldingly mounting said roller, movement of the door to an open position causing the cam surface to engage the roller and move beyond the same to permit engagement of the roller with said holding surface to yieldingly resist closing movement of the door, said roller being yieldingly held in contact with said holding surface with sufficient force to resist normal forces on the door, but yieldable to permit the door to close upon application of an abnormal force, and means for rendering the roller inoperative with respect to said holding surface to permit free opening and closing of the door.
2. The combination with a casing element and a door element hingedly associated therewith, of a guide structure embedded in one of said elements, a slide member associated with said guide member and having a cam surface and a holding surface, a link having one end pivotally connected with said sliding member and the opposite end pivotally connected with the other of said elements, a roller normally mounted in the path of said cam surface, means for yieldingly mounting said roller, movement of the door to an open position causing the cam surface to engage the roller and move beyond the same to permit engagement of the roller with said holding surface to yieldingly resist closing movement of the door, said roller being yieldingly held in contact with said holding surface with sufficient force to resist normal forces on the door but yieldable to permit the door to close upon application of an abnormal force, and buffer means arranged in the path of the sliding element to yieldingly resist further movement of the sliding element after engagement of the roller with said holding surface.
3. The combination with a door casing structure, and a door structure pivotally connected to said frame structure to swing open in either direction, of a guide housed in one of said structures, a slide slidably in said guide, a link pivotally connected at one end to said slide and at the other end to said other structure, said guide and link when in closed position occupying a space flush with the surface of the structure housing said guide, said guide being of greater length than said link and having a recess shaped to fit and house said link when in closed position, said recess being open on both sides to let said link swing out in either direction, said link moving said slide toward the pivotal axis of said door structure on opening movement in either direction, cushioning means at the end of said guide nearest said pivotal axis inaccessible to the operator and operative at all times for cushioning an opening movement in either direction, retaining means independent of said cushioning means and actuated by said slide upon movement of the parts to open position, for yieldingly resisting closing up to a predetermined force, and readily accessible manual adjustment means for preconditioning said retaining means to be operative or inoperative.
4. The combination with a door casing structure, and a door structure pivotally connected to
- said casing structure, of a guide housed in one of said structures, a slide member slidable in said guide, a link pivotally connected at one end to said slide member and at the other end to said other structure, said guide and link when the door is in its closed position terminating flush with the surface of the structure housing said guide, said guide being of greater length than the link and having a recess shaped to fit and house the link when the door is in its closed position, 5 said link moving said slide member toward the pivotal axis of said door structure during the opening movement of the latter, cushioning means at the end of the guide next said pivotal axis operative at all times for cushioning the door 10 when it is opened a predetermined amount, retaining means independent of said cushioning means and actuated by said slide member upon movement of the door to its open position, for 15 yieldingly resisting closing of the door up to a predetermined force, and manually adjustable means for conditioning said retaining means to be operative or inoperative.
5. The combination with a casing element and a door element hingedly associated therewith, of 20 a guide structure embedded in one of said elements, a slide member associated with said guide structure, a link having one end pivotally connected with said slide member and the opposite end pivotally connected with the other of said 25 elements, resilient retaining means for catching said slide in the position corresponding to the open position of the door element, and readily accessible manual adjustment means for preconditioning said retaining means to be operative 30 or inoperative.
6. The combination with a casing element, a door element hingedly associated therewith, and a spring means tending to close said door; of a 35 guide structure carried by one of said elements; a 40 slide structure associated with said guide structure and slidable along the same; a link having one end pivotally connected with said slide structure, and the other end connected with the other 45 of said elements to move said slide structure upon movement of said door; a cam member on one of said structures and a cam holding member on the other structure; said cam member having a 50 gently inclined camming surface and a steeply inclined holding surface, inclined in opposite 55 directions; resilient means holding one of said members in position to engage the other when the door is opened; said camming surface being positioned to engage said holding member first and cause deflection of said resilient means; said holding surface being positioned to engage said holding member after deflection by said camming surface and upon return from deflected position; said 60 resilient means, when said holding surface is active, having sufficient strength to resist said spring means, but yielding to permit the door to close upon application of a substantial additional force, and manual adjustment means for rendering said cam and cam holding members inoperative 65 to permit free opening and closing of the door.

ELVIN H. JOHNSON.
